Patented June 21, 1960

188,239

AUTOMOBILE EMBLEM

John H. Cericola, 218 S. 7th St., Easton, Pa.

Filed Nov. 20, 1959, Ser. No. 58,422

Term of patent 7 years

(Cl. D14—6)

Fig. 1 is a front elevational view of an automobile emblem showing my new design; and

Fig. 2 is a sectional view thereof taken on line 2—2 of Fig. 1.

I claim:

The ornamental design for an automobile emblem, as shown.
